ATTORNEY

UNITED STATES PATENT OFFICE

JACOB T. UDEN, OF NEW YORK, N. Y.

SHOE DRESSING MACHINE

Application filed October 31, 1932. Serial No. 640,398.

My invention relates to shoe dressing machines and has particular reference to machines for dressing or spraying shoes preparatory to their polishing.

The object of my invention is to provide an automatic machine, preferably operated by an electric motor, for applying shoe polish to shoes by a spraying method. This machine is especially adapted to be used in connection with my shoe shining machine as described in my Patent No. 1,881,036.

Another object of my invention is to provide a machine for spraying shoe polishing composition on shoes when the latter are on the wearer's feet, protecting at the same time the ankles above the shoe tops from the sprayed composition.

Still another object is to provide an automatic control of the spraying operation so that the latter cannot begin until the shoe is placed in the proper operating position and the ankles above the shoe tops are covered with a protective shield.

My invention is more fully described in the accompanying specification and drawing in which—

Fig. 1 is a sectional elevation of my machine in its inoperative position, Fig. 2 is a sectional end view of the same, Fig. 3 is a sectional elevation of my machine in its operating position, Fig. 4 is a sectional end view of the same, Fig. 5 is a top view of the same, Fig. 6 is a detail view of the liquid spraying nozzle, and Fig. 7 is a similar view of the powder spraying nozzle.

My machine consists of a box or housing 1 with a platform 2 for a shoe 3. The platform is supported on a collapsible or telescopic standard consisting of a plunger 4 slidably fitted in a tube 5. A spring 6 tends to keep the platform in a raised position resting against a horizontal rod 7 the ends of which are fastened in the sides of the box 1.

The housing has covers 8 with lugs 9 slidably fitted on transverse rods 10 supported in the sides of the box. The covers have trimmed portions 11 adapted to fit over the user's ankle above the shoe tops. Thick strips of sponge rubber 12 are attached to the inner edges of the covers at the recesses 11.

Thin rubber strips 13 are attached underneath to the edges of the covers so as to insure a tight joint when the covers are moved against the ankle. Springs 14 tend to keep the covers open so as to permit the foot with the shoe 3 to be inserted between these covers and to be placed on the platform 2. The outer edges of the covers have lugs 15 hingedly connected with the ends of levers 16. The latter are pivoted in brackets 17 at the sides of the box 1 and have resilient inner or lower arms 18 with rollers 19 on the ends bearing against the sides of a tapered block 20 on the end of a rod 21 attached underneath to the platform 2.

A rod 22 with a piston 23 is attached to the platform 2 and is fitted in a cylinder 24 the bottom portion of which is connected by a pipe 25 with a well 26 for a liquid shoe spraying composition 27. A ball valve 28 is placed at the bottom of the cylinder 24. An exhaust pipe 29 extends from the lower end of the cylinder 24 into an intermediate well 30 with outlet pipes 31 and 32. The pipe 31 is connected with the upper portion of a spraying well 33, and the pipe 32 is connected with a pipe 34 extending to outer nozzles of spraying guns 35. The bottom of the well 30 is connected by a pipe 36 with inner nozzles of the guns 35. The pipe 34 is also connected with one outlet of a two-way valve 37, the other outlet of which is connected with a pipe 38 leading to a shoe polishing belt for dusting the same, of a polishing machine (not shown).

The middle portion of the valve 37 is connected by a pipe 39 with a receiver 40 for the compressed air delivered by a small compressor 41 operated by an electric motor 42. Instead of having a special motor for the compressor, the latter can be also operatively connected with a motor operating a polishing belt of a polishing machine, such, for instance, as is described in my Patent No. 1,881,036, which may be placed on a common bed plate with housing 1. The motor 42 is also belted or otherwise connected with a pulley 43 of a mixer shaft 44 in the well 26. The valve 37 has a handle 45 pivotally con-

nected with the end of a rod 46 attached to the platform 2.

An additional nozzle 50 is supported on the pipe 34 under a box 51 containing a polishing powder.

The operation of my machine is as follows.

The user's foot with the shoe 3 is placed on the platform 2 which is then depressed until the plunger 4 strikes the bottom of the

10 tube 5. The plunger 22 in the cylinder 24 forces a charge of the shoe shining liquid through the pipe 29 into the reservoir 30 through the valve 48, and into the well 33 through the pipe 31. The valve 28 remains closed by the pressure from the liquid.

The air valve 37 remained disconnected from the pipe 34 until the foot began to move down, and the compressed air from the receiver 40 was flowing through the pipe 38

20 into the shoe polishing machine (not shown) for cleaning the rotating brush. At the end of the travel of the platform 2 the valve 37 is finally turned into the position shown in Fig. 3 when the air is disconnected from the

25 pipe 38 and is connected with the pipe 34. The air forces the liquid from the well 33 into the pipe 36 and into the inner nozzles of the spraying guns 35, the valve 49 being opened by the air pressure.

30 The compressed air also flows from the pipe 34 into the outer nozzles of the guns 35 thereby spraying the polishing liquid on the shoe. At the same time the air will spray a polishing powder from the box 51 by

35 the spraying nozzle 50. The bottom aperture in the box 51 is made very small so that the powder does not flow when there is no air blast from the nozzle 50. The powder will be directed only on the toe portion of the shoe.

40 After the well 33 has been emptied the air will flow through the pipe 36 and through the inner nozzles of the guns 35 thereby cleaning them from the remaining liquid. This arrangement permits the use of a predetermined portion of the polishing liquid for each shoe and eliminates waste of this liquid, preventing also the excessive spraying which may spoil the shine. The air, coming from the nozzles at the end of the operation, tends

45 to dry the polish on the shoe and to prepare same for the next or polishing operation, to be performed on a separate machine.

The ankle above the shoe tops is protected from the spray by the covers 8 which are moved together against the foot by the arms 16, when the tapered block 20 forces the rollers 19 on the ends of the legs 18 apart. The sponge rubber strips 12 press tightly

50 against the foot, and the thin rubber flaps 13, being pressed against the foot, afford additional protection, closing also a gap between the edges of the boards 8. The motor 42 operates continuously and pumps the air by the compressor 41 into the receiver 40 through

65 the pipe 47. It also turns the mixer shaft 43

in the well 27 thereby stirring the polishing liquid and preventing its sedimentation.

When the shoe is withdrawn, the springs 14 move the covers 8 apart, the block 20 being raised away from the rollers 19. The piston 23 draws a charge of the liquid from the well 27 into the cylinder 24, ready for the next operation.

When the plunger 4 moves downward under pressure from the foot, the air inside of the tube 5 is being compressed and forced out through a small hole 52. The size of the latter is so proportioned as to prevent a too rapid movement of the platform 2 thereby permitting a normal operation of the pump 23 and of the other moving parts of the machine.

Important advantages of my machine are that it is automatic in its operation, a predetermined amount of the shoe shining liquid being used for each shoe thereby insuring an even and uniform application, the shoe being sprayed from all sides; also that the operating nozzles cannot become clogged by the drying liquid as the latter is cleanly blown out at the end of each operation. The stockings are protected from the spray by covers, tightly fitting over the ankle above the shoe top, the covers being self adjusting for different thicknesses of the foot.

A throttling valve 53 may be provided in the pipe 32 in order to reduce the air passage through this pipe and to retard the flow of the liquid into the pipe 36 through the spraying well 33.

I claim as my invention:

1. In a shoe dressing machine, the combination with a housing, of a platform for a shoe in said housing, said platform being adapted to be lowered by the pressure of a foot with said shoe, means to spray said shoe with a dressing liquid when said shoe is in a lowered position, covers slidably supported on top of said housing, levers pivotally connected with said covers and extending to the bottom of said housing, a block attached to said platform and adapted to press on the lower ends of said levers thereby closing said covers around said foot when said platform is lowered, and resilient strips on the edges of said covers adapted to fit tightly over said foot thereby protecting same above said shoe from said liquid.

2. In a shoe dressing machine, the combination with a housing, of a platform for a shoe in said housing, said platform being adapted to be lowered under the pressure from a foot with a shoe, means to apply a dressing liquid to said shoe when said platform is in a lowered position, covers slidably supported on top of said housing and trimmed to fit the ankle above said shoe, elastic strips on the inner edges of said covers, a resilient means for closing said covers around said foot, said means being adapted to be operated by the

downward movement of said platform, and means to open said covers when said platform is raised.

3. In a shoe dressing machine, the combination with a housing, of a platform for a shoe in said housing, said platform being adapted to be lowered by the pressure from a foot with said shoe, a plurality of spraying guns in said housing and adapted to spray said shoe with a dressing liquid when said platform is lowered with said shoe, a source of compressed air for said guns, a storage well for said liquid, means to return said platform to its upper position, means to extract a predetermined amount of said liquid from said well, said extracting means being adapted to be operated by the upward movement of said platform, and means to deliver said amount of the liquid to said guns, said delivering means being adapted to be operated by the downward movement of said platform.

4. In a shoe dressing machine, the combination with a housing, of a platform for a shoe in said housing, said platform being adapted to be lowered by the pressure of a foot with said shoe, returning means for said platform, a plurality of spraying guns in said housing adapted to spray a dressing liquid on said shoe and adapted to be operated by compressed air, a storage well for said liquid, a spraying well for said liquid, a pump operatively connected with said platform and adapted to extract a predetermined amount of said liquid from said storage with the returning movement of said platform and further adapted to fill said spraying well when said platform is being lowered, and means to deliver said liquid from said spraying well to said guns by said compressed air.

5. In a shoe dressing machine, the combination with a housing, of a platform for a shoe in said housing, said platform being adapted to be lowered by pressure from a foot with a shoe, a plurality of spraying guns

in said housing adapted to be operated by compressed air and adapted to spray said shoe with a dressing liquid, a storage well for said liquid, a spraying well for said liquid, a pump adapted to deliver a predetermined amount of said liquid from said storage well into said spraying well and further adapted to be operated by the movement of said platform, means to deliver said liquid from said spraying well to said guns by compressed air, and means to retard the downward movement of said platform.

6. In a shoe dressing machine, the combination with a housing, of a platform for a shoe in said housing adapted to be lowered by the pressure from a foot with a shoe, a plurality of spraying guns in said housing adapted to be operated by compressed air and adapted to spray a dressing liquid on said shoe, a valve operatively connected with said platform and adapted to admit compressed air to said guns when said platform is in its lowered position, and means to spray a polishing powder to the front portion of said shoe.

7. In a shoe dressing machine, the combination with a housing, of a platform for a shoe in said housing adapted to be lowered by the pressure from a foot with a shoe, a plurality of spraying guns in said housing adapted to be operated by compressed air and adapted to spray said shoe with a dressing liquid, means to deliver a predetermined amount of said liquid to said guns, said delivering means being adapted to be operated by said platform, and a two-way valve operatively connected with said platform and adapted to admit compressed air to said guns when said platform is lowered, and further adapted to direct said compressed air outside of said housing when said platform is in its raised position.

In testimony whereof, I affix my signature.
JACOB T. UDEN.
